UNITED STATES PATENT OFFICE.

LOUIS J. FLINT, OF DETROIT, MICHIGAN, ASSIGNOR TO GRIP NUT COMPANY, OF CHICAGO, ILLINOIS, A CORPORATION OF ILLINOIS.
MAGNETO.

1,249,732.

Specification of Letters Patent. Patented Dec. 11, 1917.

Application filed September 28, 1914. Serial No. 863,836.

To all whom it may concern:

Be it known that I, LOUIS J. FLINT, a citizen of the United States, residing at Detroit, in the county of Wayne and State of Michigan, have invented a certain new and useful Improvement in Magnetos; of which the following is a full, clear, concise, and exact description, reference being had to the accompanying drawings, forming a part of this specification.

My invention relates to magnetos.

Prominent objects of the invention are to provide a simple and advantageous construction of magneto; to secure a high degree of efficiency; to arrange for the satisfactory operation of the magneto when rotated in different directions; to control the opening or breaking of the circuit with the rotation in one direction or the other, and especially to permit the circuit to be broken at the same point, when rotated in reverse directions; and to secure the foregoing and other desirable results in a simple and expeditious manner.

In carrying out my invention in the manner herein set forth I construct the distance between the pole tips at least as great, and preferably greater than the width of the peripheral portion or portions of the armature core. As a result there is no overlapping of the pole tips or pieces by the peripheral portion or portions of the armature core or the core faces, as I shall call them. Consequently the current wave will rise and fall in the same way whether the rotation of the rotary member is in one direction or the other. As a preferred arrangement I make the core face or faces of appreciably less width than the distance between the pole pieces or tips, so that there are small air spaces or gaps between the core and pole pieces or tips when the core face or faces is or are in position between the latter.

I also provide certain other new features of construction, among which is a circuit breaker capable of breaking the circuit at the same point, whether the armature be rotated in one direction or the other. I also provide an advantageous arrangement of winding, preferably consisting of a high and low tension winding or a plurality of high and low tension windings.

In the accompanying drawings Figure 1 is a side elevation of a magneto embodying my present invention;

Fig. 2 is a vertical section taken on line 2—2 in Fig. 6;

Fig. 3 is a vertical section taken on line 3—3 in Fig. 6;

Fig. 4 is an end elevation of the left hand end in Fig. 1;

Fig. 5 is a vertical section taken on line 5—5 in Fig. 6;

Fig. 6 is a horizontal longitudinal section taken on line 6—6 in Fig. 5;

Fig. 7 is a diagrammatic view showing the circuit arrangements;

Fig. 8 is a diagram of another circuit arrangement; and

Fig. 9 is a view diagrammatic in character of the field magnets and armature showing the relative arrangements of the same.

Referring to the drawings I show a simple form of magneto involving a pair of horse shoe magnets, 1 and 2, mounted upon a base piece 3. An armature 4 is mounted between pole pieces 5—5 and 6—6 at the lower ends of magnets 1 and 2, respectively. Connecting members 7—7 are preferably located between the vertical arms of the magnets 1 and 2, and secured to the latter by means of screws 8—8. The armature 4 is preferably made with a core having end members 9, Figs. 2 and 9, with laterally projecting portions or tips 9^a, the central or main body portion of the core being surrounded by an inner winding 10 and an outer winding 11, Fig. 6. The end members 9 forming the pole faces 9^b, are preferably made of slightly less width than the distance between the projecting corners 5^a—5^a, (Fig. 2), for example, of the pole pieces, whereby when the armature is in a central position, as shown in Fig. 2, and in full lines in Fig. 9, the core faces of the armature will not overlap the pole pieces but on the contrary will not quite span the same, so that there will be small air gaps 9^c between the tips 9^a and the corners 5^a. This has the result that in the current wave the rise and fall is more nearly uniform and furthermore the current wave is the same, be the armature rotated in one direction or the other.

The inner winding 10 is preferably a primary winding and the outer winding 11 a

secondary winding for the purposes more fully set forth hereinafter. These windings are suitably connected and the magneto provided with suitable mechanism so that the 5 current may be properly broken and led off in suitable manner, as for example to the spark plug of an automobile or other device.

The armature is provided at its right 10 hand end (Fig. 6) with a casing member or end 12 having an annular flange 14. Within the member 12 is located a condenser 15 which is conveniently secured to the right hand end of the armature with a metallic 15 condenser strap 16 between. This condenser 15 is made in any suitable way, being preferably made of a number of fine windings arranged or wound inductively with reference to one another and inclosed in suitable 20 insulating material such as silk or mica. The casing member 12 carries a hub portion 17, which in turn carries a ball race 18 forming part of a ball bearing, having balls 19 and an outer ball race 20. Insulating material 21 is arranged within the hub 17 and between the same and a central spindle 22. Insulating material 23 is also located at the inner end of the hub 17 and other insulating material 24 is located on the inner face of 25 the member 12. A pair of cups 25 and 26 are arranged at the right hand end of the magneto as shown in Fig. 6, these cups with coöperating and associated parts forming the circuit breaker of the magneto. These 30 two cups 25 and 26 are secured to the end of the hub 17 so as to rotate therewith, insulating material 27 being interposed between said cups. The inner cup 25 carries a contact 28 (Fig. 5), and the outer cup 26 35 is provided with a flange 29 forming with the back wall of the cup, a support or bearing for a pin 30 which forms a pivotal support for an arm 31 having one of its ends provided with a contact 32 arranged to 40 operate with the contact 28 on the cup 25. A spring 33 is carried by the cup 26 and arranged in engagement with the arm 31 whereby said spring normally tends to hold said arm in position to cause the engagement 45 of contact 32 with contact 28. A ring 35 is arranged outside of the outer cup 26 and is provided with two projections or cams 36, 36 (Figs. 5 and 6), said cams being conveniently inserted in recesses formed 50 in said ring. The cups 25 and 26, it will be seen, rotate with the armature but the ring 36 is stationary so that the cams 36—36 are held against rotation, and consequently the rotation of the cups carrying with them 55 the arm 31 causes the actuation of the latter by means of the roller 37 at one end thereof, so that said arm 31 is actuated by the roller 37 striking against the cams 36—36 twice in each revolution of the armature, thereby causing the contact 32 to sepa-

rate from the contact 28 and thereby open a circuit including said contacts, twice in each revolution of the armature, said circuit being referred to more in detail hereinafter. A pin 38 is inserted in a slot 39 70 (Fig. 5) formed in said ring and also into an aperture formed in the frame immediately surrounding said ring. This pin 38 is made removable so that it may be withdrawn, thereby permitting the ring 35 to be shifted or turned at will so as to place the cams 36—36 at different positions with relation to the armature; but this construction is used only when spark advance is desired. Shifting the position of the ring, 80 hence the cams, varies the time of break along the wave. The slot 39 allows the cam ring to turn or shift under the action of the breaker lever striking the cam points. Thus the shift of the ring will correct any error 85 of the cam points and allow breaking the circuit at the same point on the wave for either direction of rotation.

An outer casing member 40 is arranged outside of the devices just described, so as to 90 inclose the same, this casing being secured to the poles and base piece of the machine. A terminal 41 is secured to the casing 40, said terminal having a central screw threaded member or pin 42 which extends through 95 the casing 40 and makes contact with a threaded spindle 43 on the end of the spindle 22. A nut 44 is arranged upon the threaded spindle 43, said nut being adapted to hold the inner cup 25 in position. Another nut 45 is mounted upon the inner 100 end of the threaded spindle 42, said nut 45 being adapted to hold the spindle 42 in position, insulating material 46 being interposed between the nut 45 and the casing 40. 105

At the other or left hand end of the armature is located a distributing device. This distributing device comprises a rotary ring or collector 48 mounted upon the axle or shaft 49, supporting the armature. This ring 48 has a V shaped groove 50, in which are arranged brushes 51 contacting with the inner surface of the groove. These brushes 51 are mounted in sockets 52 formed in lateral projections 53 in posts 54 mounted at the sides of the armature, as shown in Fig. 3. Springs 55 are arranged within the sockets 52, said springs tending normally to push the brushes 51 into position to make contact with the inner surface of the collector ring 48. The posts 54 have vertical sockets 56 for the reception of a wire or conductor which would be inserted into said sockets and then secured therein by soldering or otherwise. Screws 57 are also shown 110 passing through the walls of the posts 54 from the sockets 52 to the sockets 56, so that said screws may be engaged with the conductors inserted into the sockets 56. The posts 54 are supported by screws 58 passing 115

through their lower ends and into blocks 59. The distributor ring 48 is divided into two parts 48^a and 48^b, (Fig. 3), separated by insulation 60. The part 48^a which is substantially half of the ring is for connection with one of the windings, as for example the outer winding 11, as by a rod or pin 60^a, (Figs. 3 and 6.) The part 48^b which is also substantially half of the ring, is an insulation casting such that when 48^a is in electrical contact with one brush 51, the insulated part or segment 48^b, is in contact with the other brush 51. Thus the current from the secondary is distributed, first to one brush 15 and then to the other, by the rotation of 48^a. An end or casing member 60^b is arranged outside of the ring 48 and a ball bearing 60^c located within the same. The condenser 15 is connected by means of a conductor 61 (Fig. 2,) one end of which runs to a condenser terminal 62 and the other end of which runs to an arm 63, from which connection is made to ground or one side of the machine. The other condenser terminal 64 is connected by a conductor 65 with a clip 66 on the ring 12, whence connection is made by a brush 67 to a terminal or post 68 mounted on the top cross piece 69. The terminal 68 has a nut 70 by which an outside conductor can be connected and held in place.

The circuit connections are best shown in Figs. 7 and 8. Referring first to Fig. 8, the distributor ring is shown at 48 and the brushes 51—51 in contact therewith. From these brushes conductors 71 and 72 run to spark plugs 73 and 74, respectively, the latter being connected to ground by conductors 75 and 76. Connection between the secondary winding and the ring segment 48^a is indicated by conductor 77, the same extending to and being connected with said ring segment 48^a by means of pin 60^a. The other side of the secondary winding 11 is connected to ground by a conductor 78. The primary winding 10 is shown connected at one end to ground by a conductor 79 whence another conductor 80 also extends from ground to a terminal 81, between which and the conductor 77 a safety gap 82 is placed. The other end of the primary winding 10 is connected with a conductor 83 which extends to the condenser 15, and thence to the binding post 70, whence a connection 84 runs to ground. A conductor 85 runs from the condenser 15 to the circuit breaker 28, 32, and thence to the binding post 41, a conductor 86 extending to connection 83^a between condenser 15 and post 70. A control circuit 87 is shown containing a switch 88 under the control of the operator.

In the arrangement of Fig. 7 the circuit connections are substantially the same, but instead of having two spark plugs only one is shown with a single conductor 71 run-

ning to the same, which is number 73, there being but the one connection to the distributor ring 48.

By adjusting the circuit breaker it will be seen as by referring particularly to Figs. 5 and 9, that the circuit will be broken at a more or less advanced position in the current wave, and this will be true no matter whether the machine be run in one direction or the other. The adjustment of the circuit breaker may be done as desired, advancing or retarding the opening of the circuit in any desired way by shifting the ring 35 in one direction or the other to the desired extent.

It will be seen further that inasmuch as the armature core does not overlap the pole pieces and consequently the current wave rises and falls in the same way, be the armature rotated in one direction or the other, it will follow that the circuit breaker will open the circuit in the same way or at the same point when in the same position of adjustment with the machine rotated in one direction or the other. It will also be seen that by the winding arrangement a high degree of efficiency and effectiveness is secured, with great strength of spark.

It will be understood that changes and modifications may be made without departing from the spirit of the invention.

What I claim is:

1. In a magneto, circuit breaking mechanism comprising in combination, a ring provided with cams, a pair of separable contacts, means for rotating said contacts, and means whereby the rotation of said contacts causes a separation of the same by said cams.
2. In a magneto, circuit breaking mechanism comprising in combination, a ring provided with cams, a pair of separable contacts, means for rotating said contacts, and means whereby the rotation of said contacts causes a separation of the same by said cams, said means comprising a pivotally mounted arm carrying one of said contacts and having an end adapted to strike against said cams when said arm is rotated.
3. In a magneto, circuit breaking mechanism comprising in combination, a ring provided with cams, a pair of separable contacts, means for rotating said contacts, means whereby the rotation of said contacts causes a separation of the same by said cams, and means whereby said ring may be adjusted to secure an adjustment of said cams.

4. In a magneto, circuit breaking mechanism comprising in combination, a ring provided with cams, a pair of separable contacts, means for rotating said contacts, means whereby the rotation of said contacts causes a separation of the same by said cams, and means whereby said ring may be adjusted to secure an adjustment of said cams, said ring being provided with a pe-

- 1 peripheral recess adapted to receive a pin for holding said ring in adjusted position.
5. In a magneto, circuit opening mechanism comprising a ring carrying a pair of diametrically located cams projecting inwardly from said ring, a pair of cups carried by the magneto armature, one of said cups being provided with a contact and the other with a pivotally mounted arm having 10 a contact cooperating with said first mentioned contact, the other end of said arm being adapted to strike against said cams when said cups are rotated by the rotation of the armature.
15. 6. In a magneto, the combination with the armature and magnet poles constructed to produce like current waves when the armature is rotated in either direction, of circuit breaking mechanism adapted to break 20 the circuit at the same point in the current wave when the armature is rotated in either direction.
7. In a magneto, the combination with the armature and magnet poles constructed to 25 produce like current waves when the armature is rotated in either direction, of circuit breaking mechanism adapted to break the circuit at the same point in the current wave when the armature is rotated in either direction, said mechanism comprising a pair 30 of separable contacts carried by the armature, and means for separating said contacts at the same points when the armature is rotated in one direction or the other.
35. 8. In a magneto, circuit breaking apparatus comprising means for breaking the circuit at the same points when the armature is rotated in one direction or the other.
9. In a magneto, the combination with the

armature and magnet pole pieces, the latter 40 being separated a distance greater than the width of the core faces of the armature, of circuit breaking mechanism comprising separable contacts, and means for separating the same at the same points in the rotation 45 of the armature when the latter is rotated in either direction.

10. A magneto comprising in combination, an armature and field magnets, the pole tips of said field magnets being separated from 50 one another a distance greater than the width of the core faces of the armature, and high and low tension windings on said armature.

11. A magneto comprising in combination, 55 an armature and field magnets, the pole tips of said magnets being separated from one another a distance greater than the width of the core faces of the armature, and high and low tension windings on said armature, 60 said armature having a diametrically arranged core and laterally projecting end portions forming the core faces, and said windings being around said core between the projecting ends thereof.

65 12. In a magneto, the combination of a ring for an elongated slot, in combination with a pin adapted to fit in said slot, said ring being provided with cams, and a circuit breaking arrangement rotating with the armature and having a device adapted to coöperate with said cams.

In witness whereof, I hereunto subscribe my name this 11th day of Sept. A. D., 1914.

LOUIS J. FLINT.
